UNITED STATES PATENT OFFICE.

CLARENCE B. WADE, OF AMERICAN FALLS, IDAHO.

GAS-GENERATOR.

1,304,225.

Specification of Letters Patent.

Patented May 20, 1919.

Application filed July 13, 1917. Serial No. 180,415.

To all whom it may concern:

Be it known that I, CLARENCE B. WADE, a citizen of the United States, residing at American Falls, in the county of Power and State of Idaho, have invented certain new and useful Improvements in Gas-Generators; and I do hereby declare the following to be a full, clear, and exact description of the invention, such as will enable others skilled in the art to which it appertains to make and use the same.

The invention relates to improvements in gas generators.

The object of the present invention is to improve the construction of gas generators and to provide a simple, practical and efficient apparatus of comparatively inexpensive construction designed for generating gas from kerosene or distillate for storage in a tank or drum for use for heating, lighting, etc., a portion of the gas as generated being utilized to supply the burner employed to furnish the heat to vaporize and gasify the kerosene or other hydro-carbon.

A further object of the invention is to provide a gas generator of this character adapted to be used in one or more units and to be conveniently installed in stoves, furnaces or elsewhere, either for furnishing the heating means for the same or primarily for the generation of gas for use in other heating or lighting devices.

With these and other objects in view, the invention consists in the construction and novel combination of parts hereinafter fully described, illustrated in the accompanying drawings and pointed out in the claims hereto appended; it being understood that various changes in the form, proportion, size and minor details of construction, within the scope of the claims, may be resorted to without departing from the spirit or sacrificing any of the advantages of the invention.

In the drawings:

Figure 1 is a side elevation of a gas generator constructed in accordance with this invention.

Fig. 2 is a plan view of the same.

Fig. 3 is a vertical sectional view of the gas generator.

Like numerals of reference designate corresponding parts in the several figures of the drawings.

In the accompanying drawings, in which is illustrated the preferred embodiment of

the invention, the gas generator comprises in its construction a base 1 constructed of suitable metal and provided with a marginal flange 2 and having a centrally arranged flanged opening 3. The base plate, which may be constructed of a size to receive one or more units of the gas generator, forms a pan which is adapted to be used as a starting receptacle and also as a water pan for supplying moisture to the gas generator. The base is provided with spaced posts 4 upon which is mounted a supporting plate 5 of circular form provided at its upper face adjacent to its periphery with an annular vertically disposed flange 6 and having its outer edge portion forming a supporting ledge 7 for a cylindrical shell or casing 8. The supporting plate has a central opening 9 and supports an inner shell or casing 10, consisting of inner and outer cylindrical walls 11 and 12 and a horizontal connecting top plate or wall 13 and forming a central upwardly tapered passage 14. The inner casing and the outer shell are arranged in spaced relation to provide an intervening space 15 through which a mixture of gas, vapor, air and moisture passes to outlet perforations 16 of the outer shell. The outer shell fits exteriorly around the flange 6 and the inner casing fits the interior of the same.

The inner casing preferably has its top wall located below the plane of the upper edge of the outer shell, the central passage 14 having a slight upward taper, as clearly shown in Fig. 3 of the drawings, and the outer shell supports a top casing 17 having concavo-convex top and bottom walls 18 and 19 and a cylindrical side wall 20 connecting the top and bottom walls. The bottom wall and the top wall present upper convex surfaces and lower concave surfaces and the bottom wall forms a dome over the inner casing and provides a space for mixing the air, gas, vapor and moisture. This mixing space or chamber 21, formed by the concave lower face of the top casing, is located above the passage 14 and is arranged centrally with relation to the same. The top casing, which forms a drying and gasifying chamber 22, is provided at the lower edge of the cylindrical side wall 20 with a depending flange 23 which is recessed at the inner face to receive the upper edge of the outer shell, whereby the top casing is firmly seated upon the outer shell. The concave face of the

dome of the mixing chamber directs the mixture outwardly and deflects the same downwardly to the annular space 15.

The mixture burns exteriorly of the outer shell 8, and the flame directly impinges against an exterior vaporizing coil 24 which may consist of any desired number of convolutions, and which is connected at its upper end 25 to the top casing at the upper portion thereof and an inlet opening 26 which is preferably flanged, as shown. The bottom supporting plate is provided with supporting arms 27, preferably four in number, and they are arranged diametrically of the supporting plate for receiving an auxiliary vaporizing coil 28 and are pierced by bolts 29 which secure clamping members 30 in engagement with the auxiliary vaporizing coil for maintaining the same firmly upon the supporting arms. The main vaporizing coil 24 and the auxiliary coil 28 are connected by branches 31 and 32 with a supply pipe 33 in communication with a suitable tank or reservoir of kerosene or other hydro-carbon or fuel and the flow of such fuel to the coils may be controlled by suitable needle valves of which the operating stems 34 and 35 are shown in Fig. 1. The other end of the coil 28 is connected by a branch 36 with a casing 37 preferably in the form of a union and provided with chambers or compartments 38 and 39 and located beneath the central passage or opening 14 of the inner shell or casing. The top wall of the chamber 38, in which there is a suitable opening, has a nozzle 40 arranged to discharge centrally of the passage 14 for supplying vapor from the auxiliary coil 28, and mounted in the lower wall of the casing is a threaded stem 41 carrying a needle 42 arranged to be moved into and out of the opening of the nozzle for the purpose of removing foreign matter therefrom. The stem extends downwardly through the flanged opening 3 of the base. The other chamber 39 is provided in its top wall with a nozzle 43 set at an angle and arranged to discharge into the opening or passage 14 of the inner casing so as to intersect the vapor from the nozzle 40 and mix with the same at the point where the vapor enters the passage or opening 14. The compartment or chamber 39 is connected with a pipe 44 communicating with the gas storage tank (not shown) and equipped with a needle valve having an operating stem 45 which controls the passage of the gas to the nozzle 43.

The top casing is provided with an outlet 46 for the gas and is connected by a pipe 47 with the said storage tank or drum (not shown), and with which the pipe 44 is also connected.

The apparatus is equipped with a water tank or receptacle 48 having a pipe 49 leading to the pan or basin of the base 1 and

having a controlling valve 50. The pan is adapted to hold suitable fuel such as kerosene, alcohol or the like, for supplying the initial heat to start the generator.

The gas from the storage tank may be used in the starting and operation of the burner of the generator and it can be used in conjunction with the vaporized fuel, or the vaporized fuel after the starting of the generator may be used without the gas. The generator, after being started, is supplied with moisture from the water tank, the water being allowed to drip into the receptacle of the base so that the heat of the generator will vaporize the water delivered to the base and the suction or upward draft of the gas and vapor through the central passage of the inner casing will cause the water vapor or moisture to be carried upward with the discharged gas and vaporized fuel, which will also draw into the central opening and the mixing chamber air to combine with the gas and vaporized fuel and moisture to provide a mixture to burn exteriorly of the perforated shell, and the flame will burn with blast force and generate sufficient heat to heat the coils 24 and 28 for vaporizing the kerosene which passes into the top casing in the form of a vapor and is highly heated and dried therein before passing to the storage tank. The hollow inner shell or casing forms a dead air space and while the construction shown is preferable it may be of course varied without changing the general arrangement or principle of operation. Various kinds of fuel may be employed and the gas generator is adapted to utilize the gas generated for operating the burner and also to vaporize a quantity of the fuel for such purpose, and the vaporized fuel and the gas may be employed independently or simultaneously. Also the dome shaped top of the mixing chamber will cause the various ingredients of the mixture to spread and commingle and thoroughly mix before passing out through the annular space between the outer shell and the inner casing.

The supplemental vaporizing coil 28 by which one member of the burner feed jet is supplied is designed to be heated by the downward radiation from the flame in the zone of combustion of the burner which, as noted, is located below the superheating retort and the primary vaporizing coil and in a plane between the side wall of said retort and the convolutions of the coil.

What is claimed is:

1. A generator having a superheating retort, an annular burner and a mixing chamber in communication with the burner, the bottom wall of the said retort being concaved to form the upper wall of said mixing chamber, a vaporizing coil in communication with a source of supply and surrounding and spaced from said retort and dis-

charging thereinto, the zone of combustion of said burner being beneath and between the side wall of the retort and said coil, and a fuel feed jet disposed to discharge axially into said mixing chamber against the concaved upper wall thereof.

2. A generator having a superheating retort provided with a downwardly concaved bottom wall, a burner disposed beneath the 10 retort and having an annular series of laterally directed discharge orifices, the said bottom wall of the retort and the burner defining a mixing chamber which is in communication with the burner orifices, a vaporizing coil in communication with a source of supply and surrounding and discharging into said retort, the combustion zone of the burner being beneath and between the side wall of the retort and said coil, and a fuel feed jet discharging axially into said mixing chamber against the concave surface of said retort bottom.

3. A generator having a superheating retort, a main vaporizing coil in communication with a source of supply and surrounding and discharging into said retort, an annular burner disposed beneath said retort and having its combustion zone between the side wall of the retort and said coil, and a supplemental vaporizing coil also in communication with a source of fuel supply and surrounding the burner adjacent to the zone of combustion thereof and having an outlet jet disposed to discharge into the burner 35 axially of its zone of combustion.

4. A generator having a superheating retort provided with a downwardly concaved bottom, a vaporizing coil in communication with a source of supply and surrounding 40 and discharging into said retort, an annular burner disposed beneath the retort and defining with the concaved bottom wall thereof an intermediate mixing chamber, said burner having an annular laterally discharging series of burner orifices whereby the combustion 45 zone of the burner is beneath and between the side wall of the retort and said coil, and a second vaporizing coil also in communication with a source of supply, surrounding the burner beneath the said zone

of combustion thereof and provided with an outlet orifice disposed to discharge axially into said mixing chamber.

5. A generator having a superheating retort, a main vaporizing coil in communication with a source of supply and surrounding and discharging into said retort, a burner disposed beneath and defining with the bottom wall of said retort an intermediate mixing chamber, said burner having an annular series of laterally discharging burner orifices in communication with said mixing chamber and also having a central inlet passage disposed axially of the burner and said mixing chamber, a second vaporizing coil also in communication with a source of supply and disposed adjacent to the zone of combustion of said burner, and fuel feed jets disposed to discharge through said passage into the mixing chamber and respectively in communication with said second vaporizing coil and a source of gaseous fuel.

6. A generator having a superheating retort, a main vaporizing coil in communication with a source of supply and surrounding and discharging into said retort, an annularly discharging burner disposed beneath and defining with the bottom wall of said retort an intermediate mixing chamber, said burner having a combustion zone disposed between the side wall of said retort and said main coil and provided with a central inlet passage in communication with said mixing chamber, a supplemental vaporizing coil also in communication with a source of supply 75 and surrounding said burner adjacent to the zone of combustion thereof, fuel feed jets disposed to discharge through said passage into the mixing chamber and the same being in communication respectively with said 80 supplemental coil and a source of gaseous supply, and an ignition pan disposed beneath said feed jet and in communication with a source of aqueous supply.

In testimony whereof I affix my signature 95 in presence of two witnesses.
